UNITED STATES PATENT OFFICE

2,517,445

POCKET RECEPTACLE FOR DISPENSING
TICKER TAPE

Sidney Ruhland, New York, N. Y.

Application July 2, 1946, Serial No. 681,004

3 Claims. (Cl. 206—37)

1

This invention relates to a pocket receptacle or holder providing a magazine for receiving a narrow elongated strip of writing paper such as ticker tape, and while not limited thereto the invention may be in the form of an automatic pencil and the writing paper arranged in the magazine in plaited or accordion folded relation.

The invention comprehends a receptacle or holder of the indicated character having a magazine extending longitudinally of the opposite sides and across the outer end thereof and which is provided with an opening at the inner end of the magazine for discharging the paper strip therethrough.

The invention further has for an object the provision of a closure member slidable with reference to the receptacle or holder for opening the magazine in order to fill the same with the paper strip and for closing the magazine to retain the paper strip therein.

The invention also provides a magazine formed with a bottom wall of undulating formation in cross-sectional configuration providing limited engagement of the paper therewith in order to reduce the frictional contact of the paper with the bottom wall and between the adjacent folds of the paper when the same is withdrawn from the magazine.

The invention has for another object the provision of means for releasably latching the closure in closed relation.

With the foregoing and other objects in view, reference is now made to the following specification and accompanying drawings in which the preferred embodiment of the invention is illustrated.

In the drawings:

Fig. 1 is a side view of a receptacle constructed in accordance with the invention.

Fig. 2 is a longitudinal transverse sectional view taken approximately on line 2—2 of Fig. 1.

Fig. 3 is a transverse vertical sectional view taken approximately on line 3—3 of Fig. 1.

Fig. 4 is a top plan view of the closure member.

Fig. 5 is a vertical sectional view taken approximately on line 5—5 of Fig. 4.

Referring to the drawings by characters of reference, the invention is illustrated in its application to a pocket receptacle or holder in the form of an automatic pencil 10 provided with a forwardly projecting conical shaped end 11 having a reduced rearward extension 12 projecting into a tubular bore 13 in the body 14 of the pencil for relative rotation of the conical

2

shaped end 11 and the body 14 to thereby effect the feeding of the lead 15 through the bore 16 in the conical shaped end 11 in any desired manner. As illustrated, a plunger 17 is provided having ears 18 disposed in longitudinally extending slots 19 opening into the bore 13 with the outer end of the plunger 17 threadedly engaging in the interiorly threaded bore 16 so as to provide longitudinal reciprocatory movement of the plunger 17 upon rotation of the conical shaped end 11 with reference to the body 14 of the pencil.

The body 14 of the pencil is formed with a channel 21 extending longitudinally from adjacent the forward end to the outer end of the opposite sides thereof and across the outer free end. The said channel is of rectangular shape in cross-sectional configuration and is defined by an inner wall 22 extending continuously throughout the channel and upper and lower walls 23 extending outwardly from the inner wall and opening through the opposite sides of the pencil. The inner wall 22 of the channel is of undulating formation in cross-sectional configuration with the outwardly curved arcuate portion thereof located centrally of the channel to thereby provide limited engagement of the innermost ply of the paper strip therewith in order to reduce the frictional contact of the paper with the bottom wall of the channel and the frictional contact between the adjacent folds of the paper when the same is withdrawn from the magazine.

In order to provide a closure for the magazine, the top and bottom walls 23 thereof are provided with oppositely disposed recesses 24 which open through the sides of the pencil and extend longitudinally thereof and across the outer free end of the pencil. A closure member 25 of U-shaped formation is provided which consists of oppositely disposed longitudinally extending leg portions 26 and 27 connected by a curved bight portion 28 at one end and which is adapted to slidably engage in the recesses 24 to form the outer wall of the magazine. The said closure member is secured in closed position by means of a teat 29 projecting inwardly from the confronting walls of the oppositely disposed recesses 24 at the end of the body and over which the rounded end 28 of the closure 26 is adapted to snap. The leg portion 26 of the closure is slightly shorter than the leg portion 27 so as to provide an opening 30 in the magazine adjacent the conical shaped end 11 through which the paper is dispensed from the magazine. The

paper is stored in the magazine as indicated in Fig. 3 of the drawings in accordion folded relation with the end of the outermost fold protruding through the opening 30 and with each fold extending continuously throughout the channel with the plaited ends of the folds located adjacent the conical shaped member 11.

The body 14 is provided with a cylindrical cavity 31 which opens through the outer end thereof for receiving spare lengths of lead which opening is closed by a plug 32 having a rounded outer end formed with an undulating outer face constituting a continuation of the undulating formation of the inner wall 22 of the channel 21.

What is claimed is:

1. In a pocket receptacle, an elongated body having opposite side walls and an intermediate wall extending longitudinally of and at right angles to said side walls and integrally connected therewith centrally thereof and said side walls projecting beyond said intermediate wall at one end thereof so as to provide a channel extending longitudinally of said body along opposite sides thereof and across said one end, said body having longitudinal recesses in said opposite side walls extending along the outer edges of said channel, a closure member slidable in said recesses in covering relation with said channel to form an outer wall therefor and providing a magazine adapted to receive a narrow strip of paper extending continuously through said channel, and said body having an opening extending into said magazine at one end thereof for withdrawing the paper therethrough.

2. In a pocket receptacle, an elongated body having opposite side walls and an intermediate wall extending longitudinally of and at right angles to said side walls and connected therewith centrally thereof and said side walls projecting beyond said intermediate wall at one end thereof so as to provide a channel extending continuously along opposite sides of said body and across said one end thereof, said body having longitudinal recesses in said opposite side walls extending along the outer edges of said channel, a U-shaped closure member consisting of parallel oppositely disposed leg portions and a bight portion connecting said leg portions at one end thereof, said

U-shaped member being slidable in said recesses to dispose the said portions in covering relation with said channel to form a continuous outer wall therefor extending along the opposite sides of said body and across the outer end thereof and providing a magazine adapted to receive a narrow strip of paper, and slotted means at one end of said body extending into said channel for withdrawing the paper therethrough.

3. In a pocket receptacle, an elongated body having opposite side walls and an intermediate wall of undulating formation extending longitudinally of and at right angles to said side walls and connected therewith centrally thereof and said side walls projecting beyond said intermediate wall at one end thereof so as to provide a channel extending continuously about three sides of said body, a closure member slidable on said body in covering relation with said channel to form an outer wall therefor and provide a magazine therein adapted to receive a narrow strip of paper extending continuously throughout the length of said channel and arranged in accordion folded relation, and said body having an opening extending into said channel for withdrawing the paper therethrough, said undulating formation of the intermediate wall providing limited engagement of the innermost ply of the paper therewith for reducing the frictional engagement of the paper with the bottom wall of the channel when the paper is withdrawn through said opening.

SIDNEY RUHLAND.
